UNITED STATES PATENT OFFICE.

FRANK E. VAN DOORN AND ELMER W. FELD, OF QUINCY, ILLINOIS, ASSIGNORS TO THE VAN DOORN COMPANY, OF QUINCY, ILLINOIS, A CORPORATION OF ILLINOIS.

ELEVATOR CAR.

Application filed March 19, 1926. Serial No. 95,998.

This invention relates to improvements in elevator car construction and particularly to the post and panel construction in such cars.

The primary object of the invention is to 5 provide a post construction which will permit the side panels of the car to be attached thereto and the joint formed by the post and panel rendered light proof.

A further object is to simplify the post 10 construction so that the same may be produced at less cost, the simplicity of construction also greatly facilitating the assembly of the posts and panels during the construction of the car.

15 Another object is to provide center and corner posts for elevator cars of a construction which will allow the panels to be directly attached to the posts, thereby eliminating the use of what, in the industry, are 20 known as panel frames or panel framing.

With these and other objects in view the present invention consists in certain novel details of construction and combinations and arrangements of parts, all as will be herein- 25 after more fully described and the novel features thereof particularly pointed out in the appended claims.

In the accompanying drawings,—

Figure 1 is an elevational view of the exterior face of a portion of the rear side of 30 an elevator car embodying the present improvements.

Fig. 2 is a similar view of the interior face of the rear side, the adjacent sides of 35 the car being shown in section.

In the corner post construction illustrated in the present instance said post is composed of two members which extend vertically of the car, one of said members having a pair 40 of arms 10, 11. This member is preferably of T-shaped cross-section being made up of metal bent upon itself to form the two arms as well as the stem 12 of the T which projects outwardly from the exterior of the car. It will be observed that arm 10 is 45 arranged parallel to the inner face of the side panel 13 and said panel is secured directly to the exterior face of said arm preferably by welding so that the inner face of 50 said arm will be unbroken or unmarred by the protruding heads of any rivets or the like.

The corner post also embodies an L-shaped member preferably made up by bending the metal upon itself so as to lend rigidity there-

to and one arm 14 of said L-shaped member lies flat against and is secured to the arm 11 of the first member by any suitable fastening means shown in the present instance as consisting of the nut and bolt 15. The 60 other arm 16 of the second member extends at right angles to arm 11 and parallel to the face of the side panel 17, said side panel being attached directly to the exterior face of arm 16, the same as panel 13 is attached 65 to the arm 10. With this construction, wherein the arms 10, 16 of the composite post extend parallel to the corner edge portions of the panels, the use of panel framing is unnecessary. Further, the two upright members comprising the composite post may be produced at a comparatively 70 low cost, and when connected together form a very rigid, substantial corner member for the car body.

In order to prevent the admission of light 75 into the interior of the car through the joint between arms 11 and 14 of the two members, one of said members is formed with a flange 80 extending transversely of said joint. Preferably, this flange, indicated at 18, is formed at the exterior end of arm 14 of the L-shaped member.

In the case of the center posts for the car body the L-shaped member of the corner 85 post is omitted and the panels 13, 19 are secured, as by welding, directly to the exterior plane surfaces of the two arms 10^a, 11^a, of the upright which is of T-shaped 90 cross-section as in the case of the corner post. The metal being bent upon itself prevents the admission of light through the joint formed by the two layers constituting the stem 12^a of the T-shaped center post, and the extent of overlap between the arms 95 10^a, 11^a and panels 13, 19 is such that no light will be admitted through these joints. The center post being a duplicate of one of the members used in the corner post further reduces the cost of producing the two forms 100 of post because the machinery or apparatus necessary for forming up the center post is identically the same machinery as is used in the production of one of the two members constituting the corner post.

105 It will be noted that in each instance the side panels are attached to the exterior surfaces of the arms of the posts. With this arrangement the arms form offsets on the interior of the car so that they have more or 110

less of an ornamental effect. In addition, the appearance of the interior of the car is much more pleasing by reason of the turned over edges of the arms than would be the case if the plane edges of the side panels, or of panel framing if the same were used, were exposed to the view of persons occupying the car.

What we claim is:

1. In an elevator car, the combination with adjacent side panels, of a vertically disposed post to which said panels are connected, said post having diverging arms located within the car and extending parallel to the inner faces of the side panels, said side panels being directly attached to the exterior faces of said arms.

2. In an elevator car, the combination with adjacent side panels, of a vertically disposed post to which said panels are connected, said post being provided with arms having plane faces arranged in parallelism to the edge portions of the inner faces of the panels, and said edge portions of the panels being directly attached to the exterior faces of said post arms, whereby the vertical edges of the post arms will be exposed on the interior of the car.

3. In an elevator car, the combination with the side panels thereof, of a corner post to which said side panels are attached, said corner post comprising a T-shaped member having a plurality of arms, and an L-shaped member having a plurality of arms, securing means extending through one arm of each of said members, and the other arm of each of said members having a side panel directly attached thereto.

4. In an elevator car, the combination with the side panels thereof, of a corner post to which said side panels are attached, said corner post comprising an upright member of T-shaped cross-section, and a second upright member of L-shaped cross-section, one arm of the L-shaped member lying flat against one arm of the T-shaped member, securing means passing through said engaging arms of the two members, and the other two arms of said members forming the corner of the car body.

5. In an elevator car, the combination with the side panels thereof, of a corner post to which said side panels are attached, said

corner post comprising an upright member of T-shaped cross-section, a second upright member of L-shaped cross-section, one arm of the L-shaped member lying flat against one arm of the T-shaped member, securing means passing through said engaging arms of the two members, and the other two arms of said members forming the corner of the car body, and means carried by one of the engaging arms of said members for obstructing the passage of light through the joint formed by said two engaging arms.

6. In an elevator car, the combination with the side panels thereof, of a corner post to which said side panels are attached, said corner post comprising an upright member of T-shaped cross-section, a second upright member of L-shaped cross-section, one arm of the L-shaped member lying flat against one arm of the T-shaped member, securing means passing through said engaging arms of the two members, and the other two arms of said members forming the corner of the car body, and a flange formed on the L-shaped member extending transversely of the joint between the arms of the two members whereby the passage of light through the joint between said joint is prevented.

7. In an elevator car, the combination with the side panels thereof, of a corner post, said corner post comprising an upright member having a pair of arms, one of said arms having one panel attached thereto and a second upright member attached to the other arm of the first member, the other panel being supported by the second upright member of said post.

8. In an elevator car, the combination with the side panels thereof, of a corner post, said corner post comprising an upright T-shaped member to one arm of which one side panel is attached, and a second upright member having a pair of arms, one of which is connected to the other arm of said T-shaped member and the other arm of which has the other side panel attached thereto, and a flange formed on one of the two connected arms, said flange extending transversely of the joint formed by the connected arms of the two members whereby the admission of light through said joint is prevented.
